UNITED STATES PATENT OFFICE.

EDGAR M. CLARK, OF NEW YORK, N. Y., ASSIGNOR TO STANDARD OIL COMPANY, OF BAYONNE, NEW JERSEY, A CORPORATION OF NEW JERSEY.

REFINING OF PETROLEUM OIL.

1,413,899.

Specification of Letters Patent. Patented Apr. 25, 1922.

Application filed April 21, 1919. Serial No. 291,504.

To all whom it may concern:

Be it known that I, EDGAR M. CLARK, a citizen of the United States, residing at New York, in the county of New York and State 5 of New York, have invented a new and useful Improvement in Refining of Petroleum Oil, of which the following is a specification.

My invention relates to improvements in the art of refining petroleum oil, and will be 10 fully understood from the following specification, taken in connection with the accompanying drawing, which illustrates diagrammatically a refining apparatus arranged for use according to the invention.

In the manufacture of light petroleum oils, such as gasoline, there are now employed 15 on a large scale cracking processes, such, for example, as that disclosed in the patent to William M. Burton, No. 1,049,667, in which 20 a charge of relatively heavy oil, such as gas oil, is subjected to distillation under high pressure (upwards of 4 atmospheres), the pressure being maintained not only in the still but in the condenser as well. In processes such as this, the pressure is controlled 25 by regulating the escape of the incondensable gas formed during the process, this gas being released at the tail-end of the condenser, usually from a small closed receiving drum into which the condenser tail-pipe discharges. In accordance with my own prior 30 Patent No. 1,132,163, the receiving drums of a relatively large number of pressure stills are connected to a single gas pipe and to a single liquid main.

In the drawing of the present application the numeral 1 designates the condenser tail-pipe of a pressure still of the type described, and the numeral 2 designates the closed receiving drum into which this tail-pipe discharges, the drum being provided with a gauge glass, as shown at 3. Into the top of the drum there is connected a gas pipe 4 which leads to a high pressure gas manifold 5. A valved connection 6 at some point along the high pressure gas line 5 opens into a low pressure gas main 7. In accordance with my prior patent above referred to the valve in this connection 6 will 45 be used for releasing all of the gases formed in a relatively large number of stills connected to the high pressure gas line 5, the pressure in this line and in all of the stills being thereby kept constant and uniform 50 throughout the system. Into the bottom of

each receiving drum 2 there will be tapped a liquid draw-off connection 8 which joins the distillate line 9.

In accordance with the present invention I make a connection to the distillate line 9 60 as by the pipe 10 and lead this connection to the first of a series of closed treating tanks. In the drawing I have for clearness and simplicity of illustration shown the pipe 10 as extending to the bottom of a closed tank 65 11 designed to represent an acid treating tank. The submerged end of the line 10 will, in general, be equipped with a distributing device, such as a perforated spider indicated at 12. Near the top of the acid- 70 treating tank 11 there will be an overflow connection 13, from which a line 14 extends to the bottom of the second closed treating receptacle 15 which is represented as of the same construction. The receptacle 15 may 75 be a washer for washing out the entrained acid from the fluids under treatment. Beyond the washer 15 there may be a soda- 80 treating tank 16 and a final washer 17, illustrated as of the same construction. There 85 will usually be one or more settling tanks in the system, as is well understood, but I have made no attempt to illustrate these. From the last of the closed treating chambers, or receptacles, 17, the overflow line 18 90 leads into the bottom of a separation tower 19, which may be in the form of a vertical cylinder preferably mounted alongside of and of the same height as the treated distillate storage tank 20. The separation tower 90 may have a dam 21 dividing the bottom of the tower midway between the point of entrance of the line 18 and the connection 22 from the tower into the bottom of the storage tank. The dam 21 may be of a height 95 about half that of the separation tank. There is provided a gas connection 23 joining the top of the storage tank 20 with the top of the separating tower 19. A gas release pipe 24 will lead from the top of the 100 separating tower to a gas absorption plant not illustrated.

The apparatus above described is in accordance with the present invention operated in the following manner:

A liquid distillate, such as gasoline, produced within the pressure stills will drain continuously through the condenser tail-pipes 1 into the receiving drums 2, where it will collect under the pressure of the opera- 110

tion, for example, 5 atmospheres, this pressure being kept constant by controlling the escape of the incondensable gas formed in the operation from the high pressure gas line 5 into the low pressure main 7 by the valved by-pass 6. When the still is in normal operation the distillate therefrom continuously accumulating in the receiving drum 2 will be continuously withdrawn 10 through the valved connection 8 at the base of the drum into the distillate line 9, the valve being regulated so as to maintain a constant level in the drum. From the distillate line 9 the crude gasoline distillate will flow through the pipe 10 to the acid-treating tank 11 to be therein subjected to the refining action of the sulphuric acid. When the level of the oil layer floating upon the acid in the tank 11 reaches the overflow pipe 13 15 oil will discharge through the latter into the washing tank 15, thence to the soda-treating tank 16, through the final washer 17, and out by the line 18 to the separating tower 19. Overflowing the dam in the latter the distillate will pass into the storage tank 20.

The flow of distillate through the acid and alkali treatment apparatus above described and into the storage tank is obtained without the use of any pumping apparatus whatever, but solely by the utilization of the constantly-maintained pressure in the receiving drums 2. As described, the contents of these drums is subjected to a uniform pressure of incondensable gas regulated by a valved by-pass 6. For example, the receiving drums 2 may be operating under a constant pressure of incondensable gases of five atmospheres. The valves in the liquid draw-off pipes 8 from each receiving drum may be so set as to cause a drop in pressure of 55 pounds through the valve, giving a pressure of about 20 pounds per square inch in the distillate line 9 and at the entrance of the line 10 which leads 40 to the treating receptacles. Since the distillate is condensed and collected in the receivers 2 under a relatively high pressure of incondensable gases formed in the cracking operation, these gases will be driven into solution in the distillate in considerable quantities. For example, the solubility of methane, which is one of the principal constituents of the incondensable gas, is about 50 1.2 volumes per atmosphere at 70° F., so that the distillate as collected in the receiver 2 will have dissolved therein several times its volume of incondensable gases. When the pressure on the distillate is initially relieved, a considerable percentage of this gas 55 will be immediately liberated and the distillate line 9 will therefore contain a mixed fluid, partly gas and partly liquid. The gas and liquid will flow together into the line 10, and through the entire series of treating tanks described. Furthermore, there will

necessarily be a drop in pressure along the length of the treating system, as the result of which a further quantity of gas will come out of solution in the oil. It will therefore be apparent that not only will the treating system receive mixed fluids initially, but there will be a considerable evolution of gas within the system itself. These results I hold to be highly advantageous for several reasons. Thus, the gas initially entering the system with the liquid distillate, as well as gases coming out of solution during the treatment, serve to effect a very thorough agitation of the oil and the treating liquids, which agitation makes for more intimate contact and adds to the efficiency of the treatment, in so far as the liquid distillate itself is concerned. The effect of the gas in this respect may be compared to that of air, the use of which for agitation purposes in the acid and alkali treatment of oils is well known. Furthermore, the manner of operation described has the advantage of treating, that is, refining, the gas simultaneously with the liquid and in the same apparatus. As a result of the treating process, therefore, there is obtained not only a refined liquid distillate, capable of being marketed either with or without further refining, but also treated gas which may be taken from the storage tank 20 and separating tower 19 by the line 24 directly to absorbers in which it may be dissolved in refined heavy naphtha to lower the specific gravity thereof and produce a marketable product directly.

Practically the entire quantity of gas dissolved in the oil will have been released therefrom by the time the oil reaches the separating tower 19. The use of the dam 105 21 somewhat assists the separation of the gas bubbles from the liquid in this tower, there being necessarily created an ascending current of liquid at the inlet side which will carry the entrained gas bubbles to the surface. In general, however, there will be a slow liberation of gas from the oil for some time after it goes to storage, and I therefore prefer to close the top of the storage tank 20 and carry off the liberated gases by 110 the connection 23 to the top of the tower 19, from which they will enter the line 24 and be utilized as described.

In the foregoing description of the operation of the apparatus I have assumed that the receiving drums 2 were released individually by their valved connections into the distillate line 9. It will be understood, of course, that it is possible to open wide the valved connections between the individual receiving drums and the distillate line, carrying the latter under the pressure of the drums, and releasing the pressure from the line 9 into the line 10 by a valve at the entrance to the latter. Which of 120 125 130

these methods of control will be employed will be dependent upon the exact arrangement of the receiving drums and of their draw-off connections. Thus, for example, 5 if the receiving drums are at different horizontal elevations, or if it is desired to meter the distillates produced in the individual stills independently, it would be required that each receiving drum be released independently through its own valve into the distillate line. If all of the receiving drums were at the same level, however, and all drums were connected by connections of the same resistance to the line 9, this line could 10 be advantageously carried under the drum pressure, the release of liquid pressure for the whole series of stills being obtained by the valve at the entrance of the line 10.

In general, the pressure through the treating system will drop continuously, so that 20 when the treated distillate and gas reaches the tower 19 there will only be sufficient pressure to raise the level of distillate to the running level of the tower and its connected tank or tanks plus the very slight pressure 25 required to force the gas issuing from the pipe 24 through the absorber system to which the latter may be connected, or into the mains or gasometer, if there be no absorber system employed. The pressure within 30 the treating system may, however, be raised at will to any point short of the pressure available in the receiving drums, either by throttling the line 18, or if the storage tank is capable of withstanding pressure by 35 throttling the line 24. It will be understood that as the pressure within the continuous treating system is increased, the percentage of material handled in the gaseous phase 40 within the system would be decreased, the gas being maintained in solution in the liquid by the pressure. As an additional means for decreasing the volume of gas handled by the system, I may employ a gas 45 tank 30 on the line 10, any desired quantity of gas being released through the valve 31 at the top of this trap. My invention, therefore, offers not only a means for continuously and simultaneously treating the distillate and gas produced by the cracking 50 stills, but also a means of regulating the relative proportions of liquid and gas handled in the treating apparatus.

While I have in the foregoing described 55 in considerable detail a process in accordance with my invention and some variants thereof, together with a form of apparatus especially designed for the carrying out of the process, it will be understood that these 60 details are illustrative only and that the invention is not limited to the precise opera-

tions or apparatus described, except in so far as such limitations form a part of the accompanying claims, in which it is my intention to claim all novelty inherent in the 65 invention as broadly as is permissible in view of the prior art.

What I claim as new and desire to secure by Letters Patent is:

1. The method of refining petroleum oils 70 which consists in maintaining a body of oil under a substantial pressure of hydrocarbon gas, in forcing the oil by such pressure through a body of an oil-treating reagent, whereby the oil and the hydrocarbon gas dissolved therein are simultaneously refined and partially releasing the gas pressure upon the oil while passing oil through said reagent. 75

2. The method of refining petroleum oils 80 which consists in maintaining a body of oil under a substantial pressure of hydrocarbon gas, and forcing the oil by such pressure through an oil-treating reagent, whereby the oil and the hydrocarbon gas dissolved therein are simultaneously refined. 85

3. The method of refining petroleum oil 90 which consists in continuously collecting a distillate of such oil under a substantial pressure of distillation gases, and continuously forcing the collected oil by such pressure through a treating apparatus in which the oil is subjected to the action of a refining reagent. 95

4. The method of refining petroleum oil 95 which consists in continuously collecting a distillate of such oil under a substantial pressure of distillation gases, continuously forcing the oil by such pressure through a closed chemical treating system and separating and collecting the treated gas and liquid issuing 100 from the said closed system.

5. The improvement in the method of continuously treating petroleum oils containing dissolved hydrocarbon gases with an immiscible liquid reagent which consists in 105 performing the treating operation in a closed system under pressure of said hydrocarbon gases and varying the pressure of said gases within the system to control the proportions of gas and liquid treated therein. 110

6. The method of refining petroleum oils 115 which consist in maintaining a body of oil under a substantial pressure of hydrocarbon gas, and forcing the oil by such pressure successively through a series of liquid oil-treating reagents, said reagents being immiscible with the oil, partially releasing the gas pressure upon the oil in each of said successive treatments, and collecting the treated gas and liquid oil issuing from the 120 said closed system.

EDGAR M. CLARK.
